Attest:

UNITED STATES PATENT OFFICE

ARTHUR B. MODINE, OF RACINE, WISCONSIN, ASSIGNOR TO MODINE MANUFACTURING COMPANY, OF RACINE, WISCONSIN, A CORPORATION OF WISCONSIN

HEAT EXCHANGE DEVICE

Application filed December 15, 1930. Serial No. 502,422.

The invention relates to radiators and has among its principal objects the provision of a construction which may be arranged within a recess in a wall or a casing so as to substantially completely fill the entire cross sectional area of the recess or casing and accomplish this without the necessity of special fittings for completing a connection between the device and the risers which enter the 10 casing or recess and extend from the supply and return of a heating system. These risers are usually introduced to the space and separated a prescribed distance from each other and in spaced relation to the side walls 15 of the recess or casing. And since it is desirable to utilize all of the cross sectional area of the interior of the casing or the radiator, the opposite ends of the radiator are usually arranged in close proximity to said 20 side walls of the recess or casing which thus arranges the ends and the inlet and outlet 25 of the radiator at one side of or beyond the ends of the risers entering the casing which necessitates employing a special fitting to connect these openings with the risers.

It is an object of the invention to provide a radiator which substantially fills the above mentioned space and which eliminates the necessity of special fittings to complete a 30 connection between the radiator and the risers.

Another object of the invention is to provide a radiator capable of resulting in the above mentioned advantages in which heat 35 radiating means is located between the risers and also between the end walls of the recess or casing and said risers with the inlet and outlet openings of the radiator in substantial alignment with the risers. Another object of the invention is to construct the means 40 which extends between the end walls and the risers so that air may circulate therethrough, be heated thereby and enter the recess or casing and be subsequently discharged in a 45 heated condition therefrom.

Another object of the invention is to provide a structure such as above with means through which the heating medium is introduced to the device, said means having a portion 50 thereof located in a manner which will

prevent condensate from interfering with the introduction of the heating media.

The invention has these and other objects, all of which will be explained in detail and more readily understood when read in conjunction with the accompanying drawing which illustrates a means for accomplishing the above enumerated advantages, it being manifest that changes and modifications may be resorted to without departing from the 60 spirit of the appended claims forming a part hereof.

In the drawing, Fig. 1 is a sectional view of a portion of a wall having a recess provided therein in which the radiator is located, the 65 recess having openings whereby air may be introduced to the heat exchange device and be discharged from the recess in a heated condition;

Fig. 2 is a sectional view taken on the line 70 2-2 of Fig. 1;

Fig. 3 is a sectional view taken on the line 3-3 of Fig. 2; and

Fig. 4 is a sectional view showing a detail 75 of construction employed in the device.

In the structure illustrated in Fig. 1, a recess 10 is formed in a wall and when so desired, a metallic casing 11 may be mounted within the recess. The casing 11 has a removable front wall 12. A grilles opening 13 is provided at the upper portion of the casing through which heated air may be discharged from the casing. The casing 11 has an opening 14 adjacent the lower end thereof and a radiator unit 15 is located in the lower 85 end of said casing and above the opening.

By referring to Fig. 3, it will be noted that the radiator unit generally designated 15 is in communication with risers 16 and 17 and therefore heating media may be supplied to 90 the radiator. Under ordinary conditions, the ends of these risers 16 and 17 are spaced a standard or prescribed distance from each other and are also spaced a certain distance from the end walls such as 18-18 of the recess. Since it is desirable to completely fill the cross sectional area of the recess or casing, the tanks or manifolds generally designated 19 and 20 of an ordinary structure are 95 arranged in close proximity to the end walls 100

18—18 which arranges said tanks or manifolds at one side of the risers between the risers and the end walls, this arranges the inlet and outlet openings of the tanks 19 and 20 at one side of the risers, which would, therefore, require a special fitting to complete the connection between the tanks 19 and 20 and the risers.

To eliminate the necessity of these special 10 fittings, the invention contemplates arranging the tanks 19 and 20 a distance from each other substantially corresponding to the distance between the risers 16 and 17 which will thus permit the radiator unit to be directly 15 connected with the risers 16 and 17 without the necessity of special fittings. The invention also contemplates the provision of means whereby the space between these tanks 19 and 20 and the end walls 18 may be utilized to heat 20 air entering and circulating through this space. To this end, it is contemplated to provide each of the tanks 19 and 20 with heat radiating fins respectively designated 21 and 22 which may be formed of separate sheets 25 of material attached to the header or tanks, or may, as shown at 23, be constructed to provide hollow extensions 25 which are spaced from each other as indicated at 26 to provide air passages between said fins. The radiator 20 tubes 15 as before stated extend between the tanks and form a communication therebetween and these tubes are provided with heat radiating fins 27 which in effect provide openings 30 between the tubes and the fins through which air may pass and contact with the tubes and fins and heat the air as it flows through the opening into the casing 11.

As before stated, the invention contemplates the provision of a means whereby any 40 accumulation of condensate taking place within the radiator will not interfere with the supply of heating media to the radiator. To this end, the inlet opening or the supply 45 riser 17 is provided with a nipple 28 which extends into the tank 20 and terminates a suitable distance above the lower portion of the tank or in other words above the liquid 50 level of any condensate which may accumulate therein. From this it can be seen that 55 heating fluid may enter the tank above the liquid level of the condensate and be distributed to the various elements forming the heating unit resulting in quiet operation of the device, eliminating pounding, etc.

55 From the foregoing description of the structure herein disclosed for accomplishing the invention, it is manifest that a simple construction is provided which will allow the unit to be connected with the risers 16 and 17 without the necessity of special fittings to compensate for the difference of distance between the risers and inlet and outlet openings of the tanks such as 20 and 19. It is further evident that the tanks 19 and 20 are spaced from the respective end

walls 18 and that means is provided in this space whereby this space and said means may function to heat air flowing through the unit at these points. It is also evident that the tubes 15 and the transversely arranged fins connected thereto will engage air entering the opening 14, heat same as it passes therethrough causing same to flow upwardly relatively to the recess or casing 11 and be discharged through the outlet opening 13 provided in the casing. By means of the removable wall 12 access to the unit and the fittings connecting the unit with the risers may be had in the event replacement or repair is found necessary.

Having thus described the invention, what I claim as new and desire to cover by Letters Patent is:

1. In a radiator the combination of tanks, and tubes arranged at one side of and connecting said tanks and hollow fins arranged upon the opposite side of said tanks and connected with said tanks, one of said tanks having a fluid inlet and the other a fluid outlet. 85

2. A heat exchange device comprised of a casing, a radiator located transversely of said casing, said radiator being comprised of tubes and means with which said tubes are connected, hollow fins extending unilaterally of said tubes between said casing and means, said fins communicating with said means and said means being respectively provided with a fluid inlet and a fluid outlet. 90

3. In a device of the kind described the combination of a wall having a recess, a heat exchange device located in the lower portion of the recess in spaced relation to the lower end thereof, said heat exchange device being extended transversely of the recess and including fluid conducting tubes and means connecting said tubes arranged transversely thereof and in spaced relation to the end walls of the recess and hollow heat radiating fins arranged between said walls and said means said hollow fins opening into said means. 100

4. In a device of the kind described the combination of members each having an opening respectively providing a fluid inlet and a fluid outlet, and having a plurality of openings provided in one side of said members and tubes providing fluid passages connected with said openings and hollow fins arranged along said members and transversely of said members upon the side of said members, opposite to that side having said plurality of openings. 115

In witness whereof, I hereunto subscribe my name this 4th day of December A. D., 1930.

ARTHUR B. MODINE.
